COMPACT

Filed Sept. 2, 1927

Walter Poranski ^{Inventor}
By his Attorney
Edward H. Evans

UNITED STATES PATENT OFFICE

WALTER PORANSKI, OF CHICAGO, ILLINOIS, ASSIGNOR, BY MESNE ASSIGNMENTS, TO SAULEN MFG. CO., OF NEW YORK, N. Y., A CORPORATION OF NEW YORK

COMPACT

Application filed September 2, 1927. Serial No. 217,274.

My present invention relates to compacts and like toilet accessories, and aims to devise articles of the general character specified which are simple in construction, which may be readily fabricated and assembled, and which are very convenient in use, being characterized by their compactness, the convenient arrangement of the various parts of the compacts, and the convenient manner of using the device for the intended purpose. Other objects and advantages of the devices of the present invention will in part be pointed out in detail hereinafter and will in part be obvious to those skilled in the art to which the present invention relates.

Referring to the drawing, wherein I have illustrated the aforesaid illustrative embodiment of the present invention:

Fig. 1 is a cross-sectional view of a compact comprising the aforesaid illustrative embodiment of the present invention;

Fig. 2 is a view, partly in section, partly in elevation, and partly broken away, showing said embodiment and particularly the hinged portion thereof;

Fig. 3 is a plan view, on a reduced scale, of the mirror-retaining ring, showing the same in full lines in its normal expanded position outside of the container, and in dotted lines in the contracted position it will be in within the container, in the position it will occupy when holding the mirror; and

Fig. 4 is a view, partly in section and partly in elevation, showing a portion of the device particularly with reference to the construction of the hinge.

Referring now to the aforesaid illustrative embodiment of the present invention, and more particularly to the drawing illustrating the same, 10 indicates the compact as a whole comprising the lower receptacle portion 11 and the upper receptacle portion 12. The lower receptacle portion 11 is preferably provided with the beaded portion 13 and the upper edge portion 14 which is preferably relatively resilient and is preferably provided with the locking portion 14'.

Within the lower receptacle 11 is the removable compact element 15 in the form of a resilient dish or container 16, the lower

portion 17 of which is of substantially the same conformation and of substantially the same curvature as the bottom of the lower receptacle 11, and the side wall 18 of which is preferably outwardly inclined so as to be brought into firm frictional engagement with portions of the side wall of the lower receptacle 11. Within the dish 16 is the powder 19 in the form of a capsule or compacted disc. The compacted disc 19 may consist either of rouge or of any desired shade or character of face powder. The sizes of the various parts thus far described are so chosen that the resilient dish 16 will be held with the necessary frictional contact within the container 11 but adapted to be sprung out of said container by the application of the necessary force.

The upper receptacle portion 12 comprises the top portion 20, the beaded portion 21 and the side or marginal portion 22, the latter having the portion 22' which is preferably resilient and which is adapted to cooperate with the locking portion 14' of the lower receptacle 11. At 23 is indicated an extension or portion of the side member 22 of the upper receptacle 12, the lower portion of which is arranged in the form of a loop 24 adapted to pass about the hinge pin 25, the ends 26 and 27 of which are flattened to prevent any undesirable circumferential movement of the hinge pin 25, portions 28 and 29 of the side wall of the upper receptacle 12 being rolled or folded in clamping position about portions of the hinge pin 25 to hold the hinge pin in place so that the upper receptacle 12 may be freely swung around the same by means of the looped portion 23 in a manner which will be readily apparent to those skilled in the art to which the present invention relates.

At 30 I have indicated a mirror and at 31 means for properly positioning the mirror within the compact proper, preferably within the upper receptacle 12. The mirror 30 is of the usual construction. The means 31 preferably comprises a ring-shaped or annular member having the inclined portion 32 and the inner flange or bearing portion 33. Normally the member 31, when outside of

the compact, has the shape shown in full lines in Fig. 3 of the drawing.

In inserting the mirror in the compact, as in the receptacle 12 thereof, the mirror is first positioned in the bottom of said receptacle and the ring then slipped in, being compressed and snapped into place with the portion 32 thereof, which preferably has substantially the same curvature as the curvature of the top portion 20 of the receptacle 12, fitting within the beaded portion 21 of said receptacle and with the portion 33 positioning the mirror and retaining the same firmly in place by the frictional engagement of the resilient portion 33 with the mirror. This manner of inserting the mirror and positioning the same is rendered altogether practical by the resilient character and by the construction of the member 31. 40 indicates a powder puff of a size adapting it to be positioned conveniently between the mirror 30 and the compact unit 18.

This completes the description of the aforesaid illustrative embodiment of the present invention. The construction of said embodiment will, it is believed, be clear from the foregoing description. Likewise the manner of assembling said embodiment will be clear from the foregoing description. It may here be noted that the ring 31 in its compressed position within the receptacle 12 assumes the form indicated in dotted lines in Fig. 3 of the drawing.

In use it will be noted that the device is altogether convenient. The compact 18 may be readily positioned within the lower receptacle and as readily removed for replacement by a fresh unit. The mirror 30 is securely held in position by resilient means which may be readily applied and as readily removed for replacement with a new mirror if the old mirror should become broken. The hinge construction is very simple and permits the device to be assembled in an expeditious, convenient and accurate manner. Other superiorities and advantages of the devices of the present invention will readily occur to those skilled in the art to which the present invention relates.

50 What I claim as my invention is:

In a compact, vanity or the like, a receptacle having a substantially circular mirror-receiving portion therein, a normally slightly elliptical resilient mirror-holding ring, and a mirror held within said mirror-receiving portion by said mirror-holding ring, the relative sizes of said mirror-receiving portion, said mirror-holding ring and said mirror being such that said mirror-holding ring is forced by said mirror-receiving portion to conform substantially to the substantially circular conformation of said mirror-receiving portion, whereby said mirror-holding ring is held in said mirror-receiving portion by a resilient pressure and said mirror-hold-

ing ring holds said mirror in place by a resilient pressure.

In testimony, whereof, I have signed my name to this specification this 4th day of August, 1927.

WALTER PORANSKI.
